UNITED STATES PATENT OFFICE.

HENRY A. FELTUS, OF MINNEAPOLIS, MINNESOTA.

RAILWAY-TRACK ATTACHMENT.

1,125,677.

Specification of Letters Patent. Patented Jan. 19, 1915.

Application filed December 22, 1913. Serial No. 808,185.

To all whom it may concern:

Be it known that I, HENRY A. FELTUS, a citizen of the United States, residing at Minneapolis, in the county of Hennepin and State of Minnesota, have invented certain new and useful Improvements in Railway-Track Attachments, of which the following is a specification.

My invention relates to improvements in railway track cross over, derailment and rerailment means, its object being to provide a construction which may be quickly set up in connection with rails for either cross over, derailment or rerailment purposes.

To this end the invention consists in the construction, combination, and arrangement of parts hereinafter described and claimed.

In the accompanying drawings forming part of this specification, Figure 1 is a plan view of a track showing my invention in connection therewith for derailment and rerailment purposes; Figs. 2, 3, and 4 are detail views of coöperating members of my invention; Fig. 5 is a perspective view of a track showing my invention arranged in co-operation therewith for cross over purposes; and Fig. 6 is a similar view to Fig. 1 looking down the track from the opposite direction.

Referring to the drawings, A and A² represent parallel rails of a track. In carrying out my invention I employ the special parts B, C, and D shown specifically in Figs. 2, 3, and 4. The part B, hereinafter termed the point member, is brought to a thin edge 2 at one end and formed on its sides with longitudinal ribs 3 to fit into the side groove 4 in the rail. The member C, hereinafter termed the frog member, is formed with a tread widened and brought to a thin edge at its end 5. The frog member C which is vertical, of general rail construction, is formed on each side with a horizontal rib 6 to fit into a corresponding groove 4 in the rail. The member D, hereinafter termed the terminal member is, as shown, of vertically general rail construction, with its upper face or tread portion 7 curved downwardly to a comparatively thin edge at the end 8. It will be noted that the members B, C and D are constructed similarly upon opposite sides so as to allow them to be ar-

ranged in connection with either side of a corresponding rail; as hereinafter pointed out.

In utilizing my features of invention for rerailment purposes I secure a point member B along the inner face of one rail as by the securing devices 9 with the tapered edge 2 of the point member B contacting with the side edge of the rail. I then secure to the opposite end of the point member, as by bolted straps 10, one of the terminal members D, the member D being held in relationship with the rail by suitable fastening means 9. I then position the frog member C upon the outer side of the opposite rail with the widened end of the flange 5 over lapping the tread of the rail, the frog member being secured in this position as by the fastening means 9. To the opposite end of the frog member I secure as by the holding straps 10 one of the terminal members D, the terminal member being held in relationship with the adjacent rail as by the fastening means 9. The members are thus in position to serve in the ordinary manner as a derailment or rerailment attachment. In derailing, as the wheels of the car pass along the rails A and A² they will run over the point and frogs, respectively, to the terminal members causing derailment. Similarly the car can be pulled up onto the rails by guiding the wheels over the terminal members. The point and frog members being similar on the two sides may be arranged in connection with the side of the rails opposite to that shown in Fig. 1. In derailment the terminal members can be dispensed with.

Where I utilize my features of invention for cross over purposes to form a spur track I arrange the same as shown in Fig. 5. In this use I secure a point member and a frog member in connection with the two rails in a similar manner to that shown in Fig. 1, except that the members will ordinarily be turned out from the rails at a greater angle. The point member is connected through an intermediate rail member 11 with a frog member 12 which overlaps the opposite rail as shown in Fig. 2. At the point where the frog member overlaps the rail, I secure to the opposite side of the overlapped rail another point member B connected with a con-

tinuing ordinary rail member 11, thus constituting the inner rail of the cross over track. The outer rail of the cross over track is formed by securing a frog member C to the outer side of the track A² parallel with the first mentioned point member. To the last mentioned frog member is secured an ordinary rail 11 in position parallel with the inner rail to constitute the outer rail of the cross over track. It will be apparent that the parts may be arranged upon opposite sides of each rail to that shown in Fig. 5, to cause the cross over track to run from the main track in the opposite direction. It will also be apparent that the angle at which the cross over track leaves the main track will be determined by the length of the rail section interposed between the point member and frog member included in the inner side of the cross over track.

As will be evident I secure by the members B, C, and D parts which are interchangeably applicable for derailment, rerailment and cross over purposes, with the same point and frog members that are utilizable in the derailment use being also usable in the cross over use. As has also been pointed out the different coöperating members are utilizable upon either side of the rail, so as to make possible derailment or rerailment from

either side of the track and the arrangement of a cross over from either side.

I claim as my invention:

1. A rail attachment of the class described consisting of a point member tapered toward one end to fit against a rail, a frog member having a top horizontal flange at one end to overlap an opposite rail and downwardly tapered terminal members movably attachable to said first members, all of said members having corresponding side faces for the purpose set forth. 35

2. In combination with a railway track, means for forming a diversion of said track comprising a point member B tapered at one end to fit against the inner side of one rail and centrally ribbed to fit underneath the tread thereof, and a frog member C formed at one end with a top flange 5 overlapping the opposite rail, said frog member 40 being similarly formed upon opposite sides and having said flange extend from opposite sides, for the purpose set forth. 45

In testimony whereof I affix my signature in presence of two witnesses.

HENRY A. FELTUS.
